JOSEPH F. GRIFFIN, OF TEANECK, NEW JERSEY, ASSIGNOR TO THE SUPERHEATER COMPANY, OF NEW YORK, N. Y.

EXHAUST STEAM OPERATED AUXILIARIES

Application filed February 8, 1929. Serial No. 338,346.

This invention relates to an apparatus for improving the efficiency of auxiliaries operated by exhaust steam from a steam engine and particularly a locomotive engine. In the operation of exhaust steam auxiliaries of a locomotive, such, for example, as the feed water heater or exhaust steam injector, it is the usual practice to take the exhaust steam either from the exhaust steam cavities of the valve chest or from the exhaust steam pipes. It is found however that the pressure of exhaust steam at such places is considerably lower than in the cylinders during the period of exhaust. To operate the auxiliaries efficiently it therefore becomes necessary, at times, to supplement the exhaust steam by live steam drawn from the boiler, or, as in stationary and marine practice where the main engine exhaust pressures are low, to restrict the free egress of exhaust steam of auxiliary engines, thus increasing the exhaust steam pressure to the desired point with a consequent loss in efficiency of the auxiliaries. With the device about to be described the exhaust steam of the main engine can be obtained at a sufficiently high pressure to enable its use without decreasing main or auxiliary efficiency. In fact the main engine efficiency will be increased due to the resulting decrease in the exhaust pressure. The taking of live steam directly from the boiler for supplementing the exhaust steam necessarily represents a drain upon the boiler and involves extra fuel consumption and therefore it is highly desirable to avoid, if possible, resorting to this expedient. It has also been found that the pressure of the exhaust steam can be considerably increased by bleeding the engine's cylinder preferably towards the latter part of the expansion stroke and that although such bleeding necessarily brings about a reduction of the steam pressure in the cylinder during a portion of the expansion stroke, the work lost, represented by this reduction of pressure in the cylinder, is more than compensated for by the advantage gained by increasing the steam pressure of the exhaust steam supply to the auxiliary. In fact the expedient of bleeding the engine's cylinder during the

expansion stroke has been practiced successfully in stationary power plants with great advantage. It has been a problem of great difficulty however to provide a practical installation for bleeding the cylinder of a simple reciprocating engine such as a locomotive engine in the manner above described for securing a pressure higher than exists in the exhaust passages. I am aware however that a suggestion has been made for equipping a locomotive with a device for performing the cylinder bleeding function but such suggestion is subject to the objection that an installation constructed in accordance therewith results in disturbing the normal events of the distributing or slide valve.

The principal object of the present invention is to provide a new and improved construction for improving the efficiency of the exhaust steam operated auxiliaries of a locomotive steam engine. Viewed from another angle the object of the present invention is to provide a new and improved construction of an installation for obtaining exhaust steam directly from the cylinders at the same instant that the distributing valve opens to exhaust steam or if desired this invention by the proper arrangement of levers etc. will permit bleeding the engine's cylinder during a portion of the expansion stroke so thereof in order to obtain for the heater, steam at a pressure higher than that of normal exhaust steam.

Another object of the present invention is to provide a new and improved construction for a valve, independent of the distributing valve, for controlling the opening and closing of suitable conduits communicating with the engine's cylinder, whereby steam for auxiliary uses will be obtained from said cylinder during the period between cut off and reversal of the piston.

A further object is to so connect said valve with a movable part of the engine that it will function to obtain the desired effect without, in any way, disturbing the normal events of the main distributing valve.

The above and other objects will appear more fully from the following more detailed description and by reference to the accom-

panying drawings forming a part hereof, wherein Fig. 1 is a side elevation of a locomotive engine showing an installation thereon constructed in accordance with the present invention, the engine's cylinder, the main distributing valve and the valve of the present invention being shown in section; Figs. 2 to 12 inclusive are diagrammatic views showing the relative positions of the distributing valve and the bleeding valve during different points of the piston's stroke, the views of Figs. 2 to 7 representing the functioning of the parts for an 85% cutoff, and Figs. 8 to 12 inclusive are views similar to Figs. 2 to 7 inclusive, 15 showing the relative positions of the valves with a 30% cutoff.

As shown in the drawings, the numeral 10 indicates the locomotive cylinder having the usual piston 11, slidably mounted there- 20 in, said piston having connected thereto the usual piston rod 12, connected to the cross- 25 head 13, slidably mounted in the crosshead guideways 14. In the particular constructional example selected for illustration the main distributing valve 15 is shown as re- 30 ceiving its motion from a valve gear of the type known as the Baker-Pilliod, the construction of which is well known. Said gear includes a plurality of links and levers, 35 the constructional details of which form no part of the present invention and therefore a detailed description of such valve gear will not be given. It will be sufficient to state that such gear includes a lever 16 known 40 in the art as the "lap and lead" lever. This "lap and lead" lever is characteristic of a number of valve gears such as the one selected for illustration in this application. In 45 each of such gears the lap and lead lever travels in what may be termed an eccentric path resulting from a combined motion imparted to the lever by connections therefrom to the driving pin and crosshead of the locomotive.

At any suitable point, immediately adjacent to the cylinder 10, a valve 17 is provided, which valve is slidably mounted within a valve chamber 18 and which chamber communicates with the cylinder 10 through the 50 conduits 19 and 20. For the purpose of the present disclosure the valve 17 and chamber 18 have been shown as integrally associated with the cylinder 10. This showing however is to be considered merely as illustrative 55 and not as limiting the invention to such integral association. It will be perfectly obvious that the casing which defines the valve chamber 18 can readily be attached to any part of the cylinder 10 and that communica- 60 tion with the interior of the cylinder can be established through external pipes rather than through cored conduits, or passages, such as indicated in the drawings.

The valve 17 has suitably associated there- 65 with a valve rod 21, which at its outer end,

is connected with a slide block 22, said block preferably being mounted within suitable guideways such as shown diagrammatically in the drawings and as indicated by the reference character 23. Connected to the slide block 22 by means of a pin 24 and slot connection 25, is the lower end of a valve actuating lever 26. The upper end of said lever is fulcrumed by a similar pin 27 and slot connection 28, upon a bracket 30, fixed to any suitable stationary support, such as the valve chest of the engine. Between its ends the lever 26 is pivotally connected by means of the pin 31 to the lap and lead lever 16, hereinbefore referred to.

From the above described construction it will be obvious that the valve 17 will have imparted to it motions in the same directions as the motions of the distributing valve 15, but due to the length of the lever 26 and the eccentric motion of the lap and lead lever 16 the motions of the valve 17 will "lead" the motions of the distributing valve 15. That is to say, the events of the valve 17 will take place in advance of the events of the valve 15.

In Figs. 2 to 7 of the drawings the principal events of the distributing valve 15 are diagrammatically illustrated and the corresponding positions of the bleeding or auxiliary exhaust valve 17 are shown.

Referring to Fig. 2 of the drawings, which shows the piston 11 nearing the end of its expansion stroke, it will be noted that the bleeding valve 17 has reached a position such that it is just about to uncover the conduit 19. The distributing valve 15 is now covering the right end port of the cylinder, and the piston 11, valve 15, and valve 17, are all travelling in the same direction as shown by the arrows. The piston has performed approximately 94% of its stroke.

It will be noted from Fig. 3 of the drawings that the valve 15 is just about to begin to uncover the right hand steam port to release the steam to the exhaust. In the meantime, the valve 17 has fully uncovered the port 19 and the piston has traversed in the interval about 3% of its stroke. The valve 15, piston 11, and valve 17, are still travelling in the same direction as shown in Fig. 2.

In Fig. 4 of the drawings the parts are shown as travelling in the opposite direction to that shown in Figs. 2 and 3. The valve 17 has closed the conduit 19 and is leading the valve 15. The latter, it will be noted, has begun to close the right hand steam port and the piston has completed about 94% of its return stroke.

Fig. 5 shows the piston 11 just as it is completing its stroke with all parts moving in the same direction as in Fig. 4.

Fig. 6 shows the distributing valve 15 just as it is about to reverse its direction of travel and when it is in a position such that the right

hand steam port is fully open to the live steam. The valve 17, in the meantime, has reversed its direction of travel and is moving from right to left. The piston has performed about 30% of its stroke as indicated.

In Fig. 7 the valve 15 is shown in cutoff position, which, in the diagrammatic views shown in Figs. 2 to 7, has been assumed to occur when the piston has performed 85% of the stroke as shown in the figure now being discussed. The valve 17 is travelling faster than the valve 15 but has not yet reached the point where the conduit 19 is opened.

It will be noted from the above that the bleeding valve is open during approximately 3% of the piston's stroke in advance of the release position of the distributing valve and that the conduit 19 will remain open during substantially the entire period of exhaust. The lead of the bleeding valve 17 over the distributing valve 15 however will cause the conduit 19 to be cut off slightly in advance of the point of closure, but, as the exhaust steam at such point is at its lowest pressure, the slight amount of steam lost in the supply to the auxiliary is negligible. During the compression period, the admission period, and the major part of the expansion period of the piston's stroke, the valve 17 maintains the conduit 19 closed, as clearly shown in Figs. 5, 6 and 7 of the drawings. The functioning of the bleeding or auxiliary exhaust valve 17 has been described above in connection with the conduit 19 and the valve events of the main distributing valve for the right hand steam port it will be understood the position of the bleeding valve with respect to the conduit 20 and the left hand steam port will be similar to those shown and described in connection with Figs. 2 to 7.

In Figs. 8 to 12 inclusive I have shown the relative positions of the auxiliary exhaust valve 17 when the valve gear is set for a 30% cutoff, the valve events correspond to those shown in Figs. 2 to 7.

It will be seen from the above that the expedient of bleeding the engine's cylinder during the expansion stroke can readily be performed with a locomotive equipped with any valve gear of the type employing a lever which receives a combined motion from the reciprocating piston or the crosshead, and the rotating driving pin, or driving rod, and that the motion for the bleeding valve is obtained from a lever connected with the so-called lap and lead lever at any desired point, the variation of which point will increase or decrease the extent of bleeding. It will also be seen that the bleeding valve will lead the distributing valve, that such bleeding valve can be located at any suitable point upon the engine's cylinder and that its presence will not, in any way, interfere with the normal events of the distributing valve. The present invention therefore enables exhaust

steam to be obtained for an auxiliary such, for example, as the feed water heater, the pressure of which steam is greatly augmented by the extraction of steam during the expansion stroke, but as the steam is extracted during such a small period of such expansion stroke, the loss of work done in the engine's cylinder is practically negligible and is more than compensated for by the increased efficiency in the operation of the feed water heater.

The valve chamber 18 is shown as provided with a flanged outlet 35 to which is connected a pipe leading the feed water heater or other auxiliary that is to be supplied with exhaust steam. In the installation shown the entire exhaust steam supply is preferably drawn from the valve chamber 18 and the usual connections between the feed water heater or other auxiliary and the exhaust steam cavities of the cylinder are omitted. It will be understood however that such usual connections may be employed and the exhaust steam supplied therethrough may be supplemented by steam from the valve chamber 18, as long as said usual connections are provided with a check valve to prevent the escape of high pressure steam from the heater or auxiliary.

While the constructional details of the embodiment of the invention selected for the present disclosure are particularly adapted for use in connection with an engine equipped with a valve gear having a lap and lead lever, it will be understood that the principles of the invention are not limited to gears of such type. As it is a primary requisite that the auxiliary valve have a motion that is a mathematical function of the motions of the piston and distributing valve it will be obvious that in any valve gear where the motion for the distributing valve is obtained directly from a rotating part such as the driving axle by the use of cams or eccentrics suitable mechanism may be connected with the valve gear for actuating the auxiliary valve.

It will likewise be understood that although the term "bleeding" has been used to describe the valve 17 and its function, the term is not used in the restricted sense as applying to the withdrawal of steam from the cylinders during the expansion stroke only but as applying to withdrawal of steam from said cylinders during any desired period of the piston's working stroke between the time of cut off to the time where reversal of the piston takes place, it being obvious that the period of such steam withdrawal may, in the particular constructional example disclosed, be readily controlled or varied as desired by varying the location of the fulcrum of the lever 26, the point of pivotal connection of said lever to the lever 16 or the point of connection to said lever 26 of the rod 21 of the valve 17.

It will likewise be understood that many

other changes, variations and modifications may be resorted to without departing from the principles of the invention.

I claim:

5. 1. The combination with the engine cylinder of a locomotive having an adjustable distributing valve gear comprising a lever which receives a motion from the crosshead and driving pin of the engine, of a second valve chamber and valve additional to the main distributing valve, conduits connecting said chamber with said cylinder, and means for operating said second valve from said lever to automatically cause the valve events thereof to lead the similar valve events of the distributing valve in predetermined accord with the varied adjustments of the latter. 70
10. 2. In a locomotive, a valve gear having a lever which receives a combined motion from the crosshead and driving pin, a main distributing valve connected with said valve gear and adjustable to varying control positions, and a second valve located adjacent to 75
15. and communicating with the engine cylinder, and an actuating lever for the latter connected to said first named lever to cause said second valve to be opened during a portion of the working stroke and also during the exhaust stroke in predetermined accordance 80
20. with the varied adjustments of the main distributing valve. 85
25. 3. In a locomotive, a valve gear having a pivotally supported lever which receives a combined motion from the crosshead and driving pin, and from which lever motion is imparted to the adjustable main distributing valve, a second pivotally supported lever actuated by said first named lever, a conduit 90
30. connecting an exhaust steam operated auxiliary to the interior of the engine cylinder, and a valve operated by said last named lever, interposed in said conduit for permitting steam to pass to said conduit during a 95
35. portion of the expansion stroke and during substantially the entire exhaust stroke in predetermined accordance with the varied adjustments of the main distributing valve. 100
40. 4. In a locomotive, a valve gear having a pivotally supported lever which receives a combined motion from the crosshead and driving pin and from which lever motion is imparted to the adjustable main distributing valve, a conduit connecting an exhaust 105
45. steam operated auxiliary with the interior of the engine cylinder, an auxiliary valve located adjacent to said cylinder for controlling the flow of steam to said conduit, a second pivotally mounted lever also receiving a 110
50. combined motion from said crosshead and driving pin, a connection between said second lever and auxiliary valve for actuating the latter, the length of the moment arm of said second lever to said auxiliary valve being greater than the moment arm of the first 115
55. lever to said distributing valve whereby the motion of said auxiliary valve will lead that of the distributing valve in predetermined accord with the varied adjustments of the latter. 120
60. 5. In a locomotive having a main distributing valve adjustable to varying control positions, an exhaust steam operated auxiliary and means for increasing the pressure of the exhaust steam supplied to said auxiliary by extracting steam from the engine cylinder during a portion of the working stroke, said means comprising an auxiliary valve mounted for reciprocation in a valve casing located adjacent to said cylinder in predetermined 125
65. accordance with the varied adjustments of the main distributing valve, said auxiliary valve being additional to, but independent of, the main distributing valve and means for operating said auxiliary valve from the valve gear of the locomotive. 130
70. 6. The combination with a locomotive engine having a cylinder, a distributing valve adjustable to varying control positions and having ported communication with both ends of said cylinder, and an exhaust steam operated auxiliary, of means for extracting steam directly from the cylinder of the engine and supplying it to the auxiliary, said means comprising a valve casing having a reciprocating valve mounted therein and means for actuating said last named valve to cause it to operate in timed relationship with said distributing valve in predetermined accord with the varied adjustments of the latter, and similarly at both ends of the piston stroke, to establish communication with said cylinder during a portion of the piston's working stroke. 135
75. 7. In a simple reciprocating steam engine, an element so connected with the distributing valve gear and with a member operated by the engine's piston that the motion of said element is a mathematical function of the motion of said piston and the adjustable main distributing valve, a chamber having passages connecting it with said cylinder, an auxiliary valve mounted in said chamber, and means connected with said element for opening said auxiliary valve during the piston's working stroke between the time of cut off and the time of the piston's reversal in predetermined accordance with the varied adjustments of the main distributing valve. 140
80. 8. In a simple reciprocating engine, a cylinder, piston and an adjustable main distributing valve and valve gear, a valve chamber communicating with said cylinder, an auxiliary valve mounted in said valve chamber, an element connected with the main distributing valve gear and with said auxiliary valve to cause the latter to be opened coincidentally with the openings of the main distributing valve for exhausting the cylinder at each end thereof in predetermined accordance with 145
85. 9. In a simple reciprocating engine, a cylinder, piston and an adjustable main distributing valve and valve gear, a valve chamber communicating with said cylinder, an auxiliary valve mounted in said valve chamber, an element connected with the main distributing valve gear and with said auxiliary valve to cause the latter to be opened coincidentally with the openings of the main distributing valve for exhausting the cylinder at each end thereof in predetermined accordance with 150

the varied adjustments of the main distributing valve.

9. In a simple reciprocating engine, a cylinder, piston and an adjustable main distributing valve and valve gear, a valve chamber communicating with said cylinder, an auxiliary valve mounted in said valve chamber, an element connected with the main distributing valve gear and with said auxiliary valve to cause the latter to be opened coincidentally with the openings of the main distributing valve for exhausting the cylinder at each end thereof in predetermined accordance with the varied adjustments of the main distributing valve, said auxiliary valve being held open during substantially the entire exhaust period of the piston's stroke.

In testimony whereof I have hereunto set my hand.
